ELECTRON GUN

Bernard C. Gardner, Philadelphia, Pa., and Archibald H. Brolly, Palo Alto, Calif., assignors to Farnsworth Television Incorporated, a corporation of California

Application May 31, 1932, Serial No. 614,500

9 Claims. (Cl. 250—27.5)

Our invention relates to electron guns or cathode ray projectors such as are used in oscilloscopes, and more particularly to such cathode ray projectors as are used in oscilloscopes employed as receiving apparatus in television or the electrical projection of pictures.

Among the objects of our invention are: To provide an electron gun capable of producing an electron stream of high intensity; to provide an oscilloscope cathode such that substantially all of the electrons emitted thereby enter the useful electron stream; to provide an oscilloscope cathode which has a focusing action to concentrate substantially all of the emitted electrons at a common point; to provide an oscilloscope cathode heated by alternating current; to provide an electron stream from an electron-emitting surface heated by alternating current unmodulated by the field produced by the heating current; and to provide an electron gun in which the interposition of a control electrode in a focused electron stream between anode and cathode does not materially change the degree of concentration.

Other objects of our invention will be apparent or will be specifically pointed out in the description forming a part of this specification, but we do not limit ourselves to the embodiment of the invention herein described, as various forms may be adopted within the scope of the claims.

Referring to the drawing:

Figure 1 is a longitudinal sectional view of an oscilloscope showing the electron gun in elevation.

Figure 2 is an enlarged longitudinal section of the cathode, anode, and control electrode comprising the electron gun as used in the device of Figure 1.

In a device of the character described, the primary object is to produce an electron stream, or pencil of cathode rays whose impact on a luminescent screen gives rise to an intense and highly concentrated spot. In order to produce such an electron stream an electron gun is used. The conventional form of electron gun has a cathode composed of a thermionic filament, the electrons from which are drawn to a plate-shaped anode having an aperture through which a portion of the liberated electrons pass. The aperture is usually provided with a nozzle or co-axial tube of narrow bore, the sides of which receive such electrons as diverge from the axis of the stream at any material angle.

The pencil of cathode rays passing through the anode is "focused" on the fluorescent screen by proper adjustment of gas pressure, electrostatic

fields, or magnetic fields sharply localized in the plane of the electron gun, the effort being to prevent divergence of the electrons within the pencil.

These prior devices are relatively inefficient because of the large number of the emitted electrons which are caught upon and held by the anode, and hence never enter the useful field. Heretofore, also filamentary cathodes have been commonly used, heated by the passage of direct current.

Broadly speaking, our invention comprises the use of a concave emissive surface raised to emission temperature by an adjacent coil of wire heated by the passage of alternating current. The opening of a beam canal in a conical projection from an anode, is placed in the focus of the concave emitter so that practically the entire electron emission passes through the beam canal and is projected onwardly toward the luminescent screen. In that way we obtain large electron densities in the final beam. The concave emissive surface is placed exteriorly on a container completely surrounding and shielding the heater coil, the field of which is thereby prevented from modulating the emission, particularly when alternating current is used.

The control electrode acts also as a shield and has in it an aperture between the emissive surface and the opening to the beam canal. This aperture is traversed by grid wires which are secured to the edge of the aperture and formed substantially concentric with the concavity of the emissive surface of the cathode.

Figure 1 shows a preferred embodiment of our device as used in a cathode ray oscilloscope for use in television, Figure 2 being a larger scale sectional view of the gun. Into one end of an envelope 1 of a heat-resisting glass such as pyrex, is sealed a reentrant stem 2. Mounted on this stem is a clamp 4 to which are welded screen supports 5 extending upwardly in the tube and welded securely to a screen ring 6 near the end of the envelope. These supports are preferably corrugated for stiffness and strength, and of a high resistance material such as nichrome or similar nickel-chromium-iron alloys.

Supported by the screen ring is a luminescent screen 7 which may be either of the well known fluorescent type, or a preferred type as described in the copending application of Philo T. Farnsworth, Serial No. 655,784, filed Feb. 8, 1933. Mounted between the screen supports is an anode 9 having a cone-shaped projection 10 which is bored out with a concentric taper to form a beam

canal 11. The taper of the beam canal may be varied, but is preferably of an angle so that a minimum of electrons can be picked up by its side walls and should correspond to the expansion of the electrons in the beam as it passes through.

Connection to a positive potential for the anode and screen ring is made by spring 12 which is sealed through the envelope at 14. The purpose 10 of the use of resistance material in the screen supports 5 is to prevent the formation of eddy currents in the supports when magnetic means are used either to deflect or focus the beam.

Mounted on stem 2 is the cathode assembly 15 which preferably comprises a container 16 of nickel or other suitable material having formed on its upper surface a spherically concave depression 17. The surface of the depression is preferably covered with an electron-emissive material 20 19, such as the rare-earth oxides having large emissivity at low temperatures, thus forming an exterior concave electron-emitting surface on the container 16. Inside the container 16 is a spiral refractory wire 20, one end of which is welded 25 to the container at 21, the other end being brought out through the hole 22 in an insulator 24 of refractory material such as lavite or isolantite. This insulator serves to position the spiral 20 in proper location within the container so that 30 all parts of the emissive surface 19 are equally heated.

In order that too great a heat may not be concentrated at the center of the emissive surface, the concavity of the heating spiral is made greater than the concavity of the emissive surface. 35 Retaining flange 25 of metal is placed over the insulator, the edges of the container are then crimped over the retaining flange, thereby completely shielding the spiral-heater wire. A very small hole is left in the retaining flange for the 40 end wire 26 to pass through, but as low voltages only are used on the heater coil only a few thousandths of an inch clearance is necessary. A cathode support wire 27 is welded to the cathode 45 and to a cathode lead wire 28, end wire 26 is welded to heater lead wire 29, and both these lead wires are sealed through the reentrant stem 2.

The cathode is placed so that the focus of the concave emissive surface is just at the opening 50 to the beam canal in the anode.

Interposed between the anode and cathode and surrounding the cathode is the control electrode 30, preferably of thimble shape, the sides of the thimble extended downwardly below the cathode 55 and acting as a shield.

The upper surface of the thimble is pierced by an aperture 31 of dimension smaller than the emissive surface, preferably circular in shape and so positioned that all of the emission from 60 the cathode emissive surface will pass through it. This aperture is traversed by grid wires 32 welded to the periphery of the aperture. As it is preferable to make these grid wires extremely fine and of a refractory metal such as tantalum 65 or tungsten, it is desirable for purposes of welding to place over them a nickel strip 34 and weld the nickel strip to the thimble; thus crushing and securely welding the refractory fine wires between the nickel strip and the thimble.

70 The grid wires 32 are shaped by any convenient tool out of the plane of the aperture, and are disposed downwardly so that each wire describes an arc concave to the top of the thimble, and the section of a sphere described by the contours of all 75 the wires is concentric with the concave emissive

surface. In this way minimum distortion of the electron stream is obtained when the control electrode is in operation.

Grid support wire 35 is welded to the skirt of the thimble and to grid lead 36 which is sealed into the stem 2. A V-shaped bend is preferably made in the grid support wire 35 so that the control electrode may be conveniently adjusted in relation to anode and cathode during assembly.

After all parts have been assembled as described, the envelope with its contents is evacuated in accordance with approved methods known in the art, filled with gas if desired, and sealed off the pumps.

In operation, alternating current is applied to 15 heater coil 20, which, being of highly refractory metal, becomes heated and heats by conduction and radiation the cathode together with its concave emissive surface, which, when at the proper temperature, emits copious electrons. Due to the 20 fact that the heater coil is entirely surrounded by the metal of the cathode container, none of the field produced by the alternation of current in the heater coil can affect the emission, and we have found that not only is the emission as free 25 from modulation as if direct current were used, but the amount of emission we obtain from an extended concave surface as described, is far greater than could be obtained from filaments as ordinarily used.

When 5-7000 volts positive potential are applied to the anode, the attraction of the end of the cone-shaped extension of the anode produces an intense electron concentration at the mouth of the beam canal, and due to the fact that all 35 portions of the concave electron-emitting surface are equidistant from the mouth of the canal, over 80 per cent of all electrons emitted enter the canal and are projected through the canal to form an intense cathode ray beam on the other 40 side. This beam may then be focused by any suitable means to create a small spot on the screen.

Beam currents of 10 milliamperes have been obtained in practice and it follows that the brilliant illumination of the screen so desirable in television is easily accomplished.

In order that picture frequencies may be used to control the intensity of the beam without disturbing the concentration of the beam, the control grid wires are formed concentric with the curvature of the emitting surface. In this manner minimum distortion of the electron stream occurs, and modulation of the beam takes place without materially disturbing the focus of the 55 electrons at the point where they enter the beam canal. In other words, the percentage of electrons entering the beam canal is maintained substantially constant during the operation of the control grid over its operating range. This removes a common source of error in prior devices, and greatly aids in the production of an undistorted picture on the luminescent screen. In addition the grid thimble acts as an effective shield between cathode and anode and tends to 60 stabilize the electrostatic fields. Such stabilization is desirable in order that stray fields from sources both inside and outside the tube may not change the direction or amount of emission before it comes under the influence of the control 65 element. It is particularly valuable in shielding the emission from the action of any deflecting means such as are commonly used, to bend the beam after it has passed through the beam canal.

We claim:

1. An oscillograph cathode comprising a container having an exterior concave electron-emitting surface, and a concave spiral-heater disposed in said container substantially parallel to said emitting surface and having a greater concavity than said emitting surface.
2. A control electrode for an electron gun which comprises a thimble having a small aperture at one end, wires fastened to said thimble and extending across said aperture, the contour of each wire describing an arc of a circle convex toward the interior of said thimble.
3. A cathode-ray tube comprising an envelope, an indirectly heated cathode having an exterior concave electron-emitting surface, a cylindrical hollow anode having an opening positioned at the focus of said emitting surface, and a control electrode shielding said cathode from said anode, said control electrode having an aperture therein between said emitting surface and said anode, said aperture being traversed by grid wires formed substantially concentric with said emitting surface.
4. A cathode ray tube comprising an envelope enclosing an electron gun, said gun including an anode having a beam canal, a cathode having a concave electron-emitting surface positioned to focus an electron beam on the opening of said beam canal when a positive potential is applied to said anode, and control elements disposed in the space between anode and cathode following an equipotential section of said beam.
5. A cathode-ray device comprising an envelope, and an anode, the combination with an electron-emitting cathode having a concave electron-emitting surface, of a control electrode comprising a plurality of wires disposed in a surface

substantially concentric with the emitting surface of said cathode.

6. A cathode-ray device comprising an envelope, and an anode, the combination with an electron-emitting cathode formed to direct the emitted electrons to a common center, of a control electrode comprising wires disposed in a geometrical surface substantially concentric with said center.

7. A cathode-ray device comprising an envelope, and an anode, the combination with a cathode having an electron-emitting portion formed to direct the emitted electrons to a common center, of a control electrode comprising a thimble surrounding said cathode and provided with an aperture over said electron-emitting portion, and having wires traversing said aperture welded to the edges of said aperture and disposed equidistant from said center.

8. A cathode ray tube having an envelope containing a cathode having an equipotential emitting surface formed to converge electrons to a common center, and a central electrode comprising a thimble surrounding said cathode and provided with an aperture between said surface and said center, said aperture being smaller than said surface and larger than said center.

9. A cathode ray tube having an envelope containing a cathode having an equipotential emitting surface formed to converge electrons to a common center, and a central electrode comprising a thimble surrounding said cathode and provided with an aperture between said surface and said center, said aperture being smaller than said surface and larger than said center, said aperture being of substantially the same diameter as the beam in the plane of the aperture.
